UNITED STATES PATENT OFFICE.

LAURA A. CLIMER, OF CHICAGO, ILLINOIS.

DOOR-HANGER.

SPECIFICATION forming part of Letters Patent No. 633,808, dated September 26, 1899.

Application filed June 26, 1899. Serial No. 721,842. (No model.)

To all whom it may concern:

Be it known that I, LAURA A. CLIMER, a citizen of the United States, residing at Chicago, in the county of Cook and State of Illinois, 5 have invented a new and useful Improvement in Door-Hangers, of which the following is a specification.

My invention consists in an improved door-hanger; and my especial object is to provide a 10 simple, cheap, and particularly effective ball-bearing hanger of this nature.

In the accompanying drawings, which show my improved hanger in its preferred form in use in connection with a door, Figure 1 is a 15 broken or fragmentary elevational view of a structure having a door suspended by means of the improved hangers; Fig. 2, an enlarged vertical transverse section at line 2 of Fig. 1, and Fig. 3 an inner face view of a detached 20 ball cup or cage.

In the preferred construction each hanger is supplied with a relatively large track-ball which travels between an upper and a lower track-rail and is itself antifrictionally journaled on ball-bearings in two flanking ball 25 cups or cages carried by the hanger. Normally the track-ball rolls on the lower track-rail; but when the door is lifted its contact is changed to the upper rail, whereby derailing 30 is prevented and binding rendered impossible.

A represents a door; B, uprights flanking the door at the desired distance apart; C, a cross-beam; D D', upper and lower track-rails, respectively, and E E hangers mounted on 35 said track and attached to the door.

Each hanger-frame comprises, preferably, an inverted-U-shaped member having an inner vertical side piece a, top connecting-web a', outer vertical side piece a'', a downward-extending attaching-shank a'', and a separately-formed block a⁴, secured by a rivet a⁵ and forming, virtually, a lower web joining the two side pieces.

Each hanger-frame preferably is equipped 45 with one track-ball F, confined between annular rows of bearing-balls b b', contained in removable cups G G', respectively. The hanger-frame is cast or formed integrally, with the exception of the block a⁴, and is provided with annular perforations to receive 50 the cups G G'. The cups, preferably of steel, are formed with flanges c and inner retain-

ing-lips c', the former of which fit into annular recesses, so as to be flush with the outer surfaces, as shown. Screws d, the heads of 55 which when countersunk bear partly on the flanges c, serve to secure the cups in place. Retaining-washers may be provided for the balls, if desired, though none are shown.

The rails D D' are of less thickness than 60 the block a⁴, and spaces are also provided above and below them to obviate danger of binding. The rails are concaved to receive the track-balls, and the upper rail is only sufficiently above the track-balls to afford the 65 necessary clearance. Thus confined it is impossible for the door to get off the track or to bind.

The track-rails are preferably of steel and are secured together at the ends by common 70 supporting-brackets H. These brackets may be dispensed with, however, and direct attachment to the building structure employed. Where used, they will be of suitable form to adapt them to the conditions present. Where 75 secured to uprights, as shown, they may be simply short angle-irons.

The hanger is adapted for use with doors and gates in many situations, such as barn-doors, elevator-doors, parlor-doors, &c. The 80 form of the hanger-frame and its mode of attachment to the door may be varied to suit varying conditions. Any required number of hangers may be used on a door, and where the track is a long one it may become desirable to provide intermediate supports for the lower rail, in which case said rail could not be completely encircled by the hanger-frame, 85 as is evident.

The track-ball may be replaced by an anti-frictionally-journalized revolving member of other form and many of the advantages of my construction still be retained. In operation the track-ball while performing the function of a shaft revolving on an axis normal to the 90 door also shifts or turns in other directions, whereby new wearing-surface is constantly 95 presented to the points of contact.

What I claim as new, and desire to secure by Letters Patent, is—

1. The combination of a door, or the like, 100 suitably-supported upper and lower track-rails, a hanger-frame secured to the door, and a track-ball confined between said rails and

antifrictionally journaled in said hanger-frame, substantially as and for the purpose set forth.

2. A hanger for doors, or the like, comprising a frame having vertical side pieces separated by a space and joined together by a web, ball-cups in said vertical side pieces, annular rows of balls in said cups, and a track-ball journaled between and upon said annular rows of balls, substantially as and for the purpose set forth.

3. A hanger, comprising vertical side pieces a^2 , top web a' , ball-cups G G' , balls in said cups, track-ball F , separately-formed block

a^4 constituting a bottom web, and means of attachment to a door, or the like, substantially as and for the purpose set forth.

4. The combination with a door, or the like, of a track-rail provided with a concave surface, a track-ball engaging said concave surface, and a hanger-frame provided with anti-friction-bearings for said track-ball and with means of attachment, substantially as and for the purpose set forth.

LAURA A. CLIMER.
